UNITED STATES PATENT OFFICE

VINCENT TOPE, OF SHARPSVILLE, PENNSYLVANIA

INGOT-MOLD FLASK

Application filed February 25, 1929. Serial No. 342,360.

My invention relates to certain new and useful improvements in flasks for casting ingot molds, and important objects of the invention are to provide a flask of the character described, which will expedite ingot mold casting operations, which embodies novel means facilitating the removal of the cast ingot mold therefrom, and which may be repeatedly reused for ingot mold casting operations.

Further objects of the invention are to provide a device of the class stated which is simple in its construction and arrangement, strong, durable and efficient in its use, and comparatively inexpensive to manufacture, maintain and operate.

With the foregoing and other objects in view which will appear as the description proceeds, the invention resides in the combination and arrangement of parts and in the details of construction hereinafter described and claimed, it being understood that changes in the precise embodiment of the invention hereinafter disclosed can be made within the scope of what is claimed without departing from the spirit of the invention.

In the drawing wherein like numerals of reference designate corresponding parts throughout the several views:

Figure 1 is a side elevational view of an ingot mold flask constructed in accordance with the invention.

Figure 2 is a top plan view thereof.

Figure 3 is a sectional view on line 3—3, Figure 2.

Figure 4 is a sectional view on line 4—4, Figure 2.

Figure 5 is a plan view of a clamp member.

Figure 6 is an enlarged view of the releasable connecting bolts.

Figure 7 is an enlarged view of the gate block.

Referring in detail to the drawing 1 denotes the hollow body portion of my improved flask which is vertically divided into four separate complementary quarter sections, respectively indicated at 2, 3, 4 and 5. The sections 2 and 3 are identical in construction and sections 4 and 5 correspond in construction.

The periphery of each of the sections 2, 3, 4 and 5, is provided with three vertically disposed, integrally formed, re-enforcing ribs, respectively indicated at 6 and 7 and with four horizontally disposed, circumferentially extending, re-enforcing ribs, respectively indicated at 8, 9, 10 and 11, which are merged at intersections with the vertical ribs 6 and 7. The vertical ribs 6 of each of the sections 2, 3, 4 and 5 are disposed at respective sides thereof, while the other vertical rib 7 is disposed centrally between the associated ribs 6. A staple 12 is fixed adjacent to each end of the ribs 7 to facilitate connections for handling independent sections 2, 3, 4 and 5.

The adjacent ribs 6, of the sections 3 and 5, and of the sections 2 and 4, are respectively joined together with a plurality of bolts 13, which extend horizontally through registering apertures 6' provided therefor in opposed ribs 6 of the sections 3 and 5, and of the sections 2 and 4.

Each of the bolts 13 is secured in position by a flat wedge 14, which extends through a slot 15 formed adjacent to one end of the bolt 13. A retaining bolt 16 extends through the lower narrow end of each of the wedges 14, to prevent the latter's dis-engagement from its bolt slot 15 unless desired.

The adjacent vertical ribs 6 of the sections 2 and 3, and of the sections 4 and 5 are respectively clamped together by a plurality of substantially U-shaped clamps 17. Each portion of the ribs 6, that is disposed between respective horizontal ribs 9, 10, 11 and 12, decreases in width from its upper to its lower end, whereby a pair of such associated rib portions provide a substantially wedge-shaped structure. When the clamps 17 are positioned to overlap the latter and forced downwardly thereon, they will function to respectively clamp the sections 2 and 3 and the sections 4 and 5, securely together. The opposed sides of associated ribs 6 are respectively provided with dowels 30 and with corresponding apertures 31 to facilitate the positioning of the sections 2, 3, 4 and 5, relatively to each other.

When the bolts 13 are secured in the adjacent ribs 6 of the sections 3 and 5, and in

the opposed ribs 6 of the sections 2 and 4, and when the clamps 17 are in their securing positions on the adjacent ribs 6 of the sections 2 and 3 and on the opposed ribs 6 of the sections 4 and 5, in the manner stated, all of the sections 2, 3, 4 and 5 are properly joined together to constitute the flask body portion 1 having a large vertically extending flask opening 18, which is open at both ends and 10 gradually and slightly increasing in area from its upper to its lower end.

The sections 2 and 3 are formed to combinedly form a vertically extending, laterally disposed, offset portion 19, in which the 15 vertically extending pouring gate 20 is provided. The lower end of the latter communicates with a horizontally extending recess 21, which is disposed adjacent to the lower end of the body portion 1 and communicates with the flask opening 18.

The recess 21 is adapted for the reception of a replaceable refractory gate block 22. The latter is formed with a passage 23 which communicates with the flask opening 18 and 25 the vertical pouring gate 20.

When preparing my improved flask for pouring the metal, a gate stick 24 is positioned centrally in the pouring gate 20 with the lower end thereof inserted in the communicating end of the block passage 23.

Suitable sand is then tamped around the gate stick 24 and the latter withdrawn leaving a continuous pouring passage through the tamped sand which communicates with flask 30 opening 18, through the inter-communicating block passage 23. By this construction the metal, during the pouring operation, will never contact with or damage the pouring gate 20 and block recess 21. Of course, before each casting operation it will be necessary to resand the pouring gate 20 and to replace the gate block 22. The pouring gate 40 20 is further provided with a plurality of vents 25 to dissipate potential gases created 45 during the pouring operation, which would otherwise tend to disrupt the sand structure in the pouring gate 20.

A pair of opposed recesses 26 are formed at the upper end of the inner periphery of the 50 body portion 1. Each of the recesses 26 is combinedly formed between respective adjacent sections 2 and 4 and the sections 3 and 5. The recesses 26 provide for casting correspondingly shaped lugs upon the ingot 55 mold being cast, to facilitate its handling.

The handling of the ingot mold being cast is further provided for by combinedly forming another recess 27 between the sections 2 and 4. A lifting loop 28 is adapted for being 60 properly sanded in the recesses 27, so that the free ends of the former are integrally embedded in the ingot mold, being cast, during the casting operation.

Another recess 29 is combinedly formed between these same sections 2 and 4. The re-

cess 29 is comparatively shallow and is intended to be properly sanded to receive a suitable impress providing identifying characteristics on the ingot mold being cast.

All surfaces of the body portion 1, including the surface of the flask opening 18, are properly sanded before each casting operation, so that the damage to the flask is reduced to a minimum, thereby permitting of the use of the same flask for repeated casting operations.

During ingot mold casting operations, the usual sanded core bar, (not shown) is, of course, positioned in the flask opening 18, so that the ingot mold casting acquires the 80 conformation of an ingot mold of regulation configuration.

In releasing the cast ingot mold from my improved flask, the wedges 14 are driven upwardly to slightly release the bolts 13, and the clamps 17 are removed entirely. Such release of the bolts 13 will allow a slight disengagement of the connection of the sections 2 to 4, and 3 to 5, while the removal of the clamps 17 will permit of the parting of the connections of the sections 2 to 3 and 4 to 5. The release of the sections 2, 3, 4 and 5, in the manner stated, will facilitate and expedite the removal of the cast ingot mold from the flask body portion 1.

The present invention provides a most efficient flask for facilitating and expediting ingot mold casting operations in an economic manner.

What I claim is:

1. In an ingot mold flask of the character described, a hollow body portion comprising a plurality of vertically divided sections, means for securing one side of each of said sections to the adjacent side of one of the adjacent sections and operable for effecting only the partial release thereof, and means for securing the other side of each of said sections to the adjacent side of the other of the adjacent sections and operable for effecting the full release of said sections secured thereby.

2. In an ingot mold flask of the character described, a hollow body portion comprising a plurality of vertically divided sections, means for securing one side of each of said sections to the adjacent side of one of the adjacent sections and operable for effecting only the partial release thereof, means for securing the other side of each of said sections to the adjacent side of the other of the adjacent sections and operable for effecting the full release of said sections secured thereby, one pair of adjacent sections combinedly formed to provide a vertically extending pouring gate and further to provide a horizontally disposed recess communicating with said pouring gate and with the interior of said body portion.

3. In an ingot mold flask of the character

- described, a hollow body portion having its periphery provided with a plurality of reinforcing ribs, said body portion being divided vertically into four complementary quarter sections, means mounted in respective ribs for securing one side of each of said sections to the adjacent side of one of the adjacent sections and operable for effecting only the partial release thereof, and means engaging respective ribs for clamping the other side of each of said sections to the adjacent side of the other of the adjacent section and removable for effecting the full release of said sections secured thereby.
- 10 4. In an ingot mold flask of the character described, a hollow body portion having its periphery provided with a plurality of reinforcing ribs, said body portion being divided vertically into four complementary quarter sections, means mounted in respective ribs for securing one side of each of said sections to the adjacent side of one of the adjacent sections and operable for effecting only the partial release thereof, means engaging respective ribs for clamping the other side of each of said sections to the adjacent side of the other of the adjacent sections and removable for effecting the full release of said sections secured thereby, one pair of adjacent sections combinedly formed to provide a vertically extending pouring gate and further to provide a horizontally disposed recess communicating with said pouring gate and with the interior of said body portion.
- 20 5. In an ingot mold flask of the character described, a hollow body portion having its periphery provided with a plurality of reinforcing ribs, said body portion being divided vertically into four complementary quarter sections, means mounted in respective ribs for securing one side of each of said sections to the adjacent side of one of the adjacent sections and operable for effecting only the partial release thereof, means engaging respective ribs for clamping the other side of each of said sections to the adjacent side of the other of the adjacent sections and removable for effecting the full release of said sections secured thereby, one pair of adjacent sections combinedly formed to provide a vertically extending pouring gate and further to provide a horizontally disposed recess communicating with said pouring gate and with the interior of said body portion, and means fixed in each of said sections to facilitate the handling thereof.
- 30 6. In testimony whereof I affix my signature.
VINCENT TOPE.
